(57) **CLAIM**

The ornamental design for an AC port damper assembly as shown and described.

DESCRIPTION

FIG. 1 is a front perspective view of an AC port damper assembly showing the new design.

FIG. 2 is a bottom plan view thereof.

FIG. 3 is a top plan view thereof.

FIG. 4 is a right side elevational view thereof.

FIG. 5 is a left side elevational view thereof.

FIG. 6 is a front elevational thereof.

FIG. 7 is a rear elevational view thereof.

FIG. 8 is a front perspective view of a ventilation damper door of the ventilation damper assembly of FIG. 1.

FIG. 9 is a right side elevational view thereof.

FIG. 10 is a left side elevational view thereof.

FIG. 11 is a bottom plan view thereof.

FIG. 12 is a top plan view thereof.

FIG. 13 is a front elevational thereof; and,

FIG. 14 is a rear elevational view thereof.

The broken lines in the drawings depict portions of the AC port damper assembly that form no part of the claimed design. The dash-dot-dash lines in the drawings depict boundaries of the claimed design. The AC port damper assembly is shown with a symbolic break in its length. The appearance of any portion of the AC port damper assembly between the break lines forms no part of the claimed design.
